UNITED STATES PATENT OFFICE.

JOHN H. HARSHAW, OF ATKINS, ARKANSAS.

GRAPPLE.

1,298,702.

Specification of Letters Patent.

Patented Apr. 1, 1919.

Application filed August 3, 1918. Serial No. 248,193.

To all whom it may concern:

Be it known that I, JOHN H. HARSHAW, a citizen of the United States, residing at Atkins, in the county of Pope and State of Arkansas, have invented certain new and useful Improvements in Grapples, of which the following is a specification, reference being had to the accompanying drawings.

This invention relates to certain improvements in grapples and has relation more particularly to a device of this general character especially adapted for use in deep wells or the like, and it is an object of the invention to provide a device of this general character having novel and improved means whereby the same may be caused to effectively grasp an article desired to be lifted or withdrawn.

It is also an object of the invention to provide a novel and improved grapple including relatively movable jaws having co-acting means for maintaining the jaws separated.

An additional object of the invention is to provide a novel and improved grapple embodying two resilient members connected one to the other and wherein the inherent resiliency of the members serves constantly to urge the working ends of the members one toward the other, together with means co-acting with said members for regulating the tension thereof.

The invention consists in the details of construction and in the combination and arrangement of the several parts of my improved grapple whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a view in side elevation of a grapple constructed in accordance with an embodiment of my invention;

Fig. 2 is a view in edge elevation of the grapple as herein disclosed;

Fig. 3 is an enlarged fragmentary view in perspective of the connecting end portions of the arms as herein employed for main-

taining the jaws of the grapple separated; 55 and

Fig. 4 is a fragmentary view in perspective illustrating a jaw constructed in accordance with a further embodiment of my invention. 60

As disclosed in the accompanying drawings, 1 denotes an elongated resilient strip which is provided at one end with an opening 2, through which extends a ring 3. Secured to the ring 3, is a connection C whereby the device may be lowered or raised in accordance with the requirements of practice. 4 denotes a second elongated resilient plate or strip which is secured at one end as at 5^a, to the plate 1. 65

The outer or working end portions of the strips 1 and 4 are of substantial duplicate construction and as is particularly illustrated in Figs. 1 and 2, each of said strips has its outer or working end portion bifurcated as at 5 with the resultant forks 6 flattened and outwardly disposed relative to the outer flat face of the member. The outer end portions of the forks 6 are provided with the inwardly directed upwardly bevelled teeth 7, as are particularly disclosed in Fig. 1. 70

Supported by each of the forks 6 and intersecting the space therebetween is a bolt 8, and loosely engaged with said bolt for 75 swinging movement in a direction longitudinally of the adjacent strip 1 or 4, is an arm 9. The inner end portions of the arms 9 are in over-lapping relation and pivotally connected one with the other as indicated 80 at 10. These arms form a jointed spreader 85 for the lower ends of the gripping device.

In order to prevent the arms 9 from passing beyond the center when said arms are maintaining the working end portions of the strips 1 and 4 in separated relation, I provide the inner ends of the arms 9 with the laterally directed lugs 11, extending one toward the other and adapted to abut, as is clearly illustrated in Fig. 3. 90

In practice the jaws 7 are separated and the spreader is shifted to the position shown in Fig. 1, the device is lowered into a well or the like to engage the object which it is desired to lift or withdraw. As the arms 9 come into contact with the object the jointed ends of the arms will be forced upward beyond the center, and thereupon the resilience 100 105

of the strips 1 and 4 will cause the jaws 7 to be urged toward each other to grasp the object.

In order that the tension of the strips 1 and 4 may be regulated I dispose loosely through the strips 1 and 4, adjacent the connection 5^a, a bolt 12. In threaded connection with the bolt 12 is a nut 14 or the like, which contacts with the strip 4. The adjustment of the nut 14 longitudinally of the bolt 12 will effectively regulate the tension of the strips 1 and 4 when the working end portions thereof are separated.

In order to hold the gripping jaws gripped upon an object when the spreader has been released, I provide the sleeve S. Normally this sleeve is disposed adjacent the bolt 12 but when the jaws move inward on the object to be grasped, the sleeve will slip 20 down on the shanks 1 and 4 and prevent outward movement of the shanks.

Fig. 4 illustrates a working jaw particularly adapted for use in connection with cylindrical objects, and as illustrated in said figure the lower end portion of the plate 1^a is provided with the inwardly directed flange 15 extending entirely thereacross and substantially perpendicular thereto the working edge 16 of the flange 15 being concavely 30 curved.

It will be seen that with this device it is possible, by means of the bolt and nut 12 and 14, to so regulate the tension of the resilient shanks or strips 1 and 4, that they will grip the object either with relatively great force or with relatively slight force and furthermore it will be noted that the tension may be increased from time to time as the natural or inherent resilience of the shanks becomes reduced through use.

It will furthermore be noted that by forming the strips or shanks 1 and 4 as illustrated in the drawings, that is, by twisting the material forming the fork 6, I secure strength 45 at the gripping ends of the members, while permitting the shanks and jaws to be formed each of one piece of material. Thus I reduce the cost of manufacture and render the device particularly simple.

I claim:

1. A grapple comprising two opposed resilient shanks contacting with and attached to and lying flat against each other at their upper ends, the shanks at their lower ends being formed with inwardly projecting grappling jaws, a spreader disposed between the lower ends of the shanks comprising arms pivoted to each other and at their outer ends pivoted to the lower end portions of the shanks, whereby when the arms are turned 60 into alinement the lower ends of the shanks will be spread apart, the arms being provided with means preventing the movement of said arms beyond a center when the lower ends of the shanks are spread, and means disposed below the point of attachment of the shanks whereby the angle of divergence of the upper ends of the shanks may be adjustably limited.

2. A grapple comprising two opposed resilient shanks contacting with and attached to and lying flat against each other at their upper ends, the shanks at their lower ends being formed with inwardly projecting grappling jaws, a spreader disposed between the lower ends of the shanks comprising arms pivoted to each other and at their outer ends pivoted to the lower end portions of the shanks, whereby when the arms are turned 75 into alinement the lower ends of the shanks will be spread apart, the arms being provided with means preventing the movement of said arms beyond a center when the lower ends of the shanks are spread, a bolt passing through the shanks below the point of attachment 80 thereof and having a nut thereon whereby the angle of divergence of the upper ends of the shanks may be adjustably limited, and a sleeve surrounding the shanks just below said bolts and having sliding movement on the 85 shanks when the shanks are shifted toward each other.

In testimony whereof I hereunto affix my signature in the presence of two witnesses.

JOHN H. HARSHAW.
